Attorney

UNITED STATES PATENT OFFICE.

WILLIAM T. SNYDER, OF BURNS, NEW YORK.

FOUNTAIN-BRUSH.

1,237,567.

Specification of Letters Patent. Patented Aug. 21, 1917.

Application filed January 25, 1917. Serial No. 144,441.

To all whom it may concern:

Be it known that I, WILLIAM T. SNYDER, a citizen of the United States, residing at Burns, in the county of Allegany and State 5 of New York, have invented certain new and useful Improvements in Fountain-Brushes, of which the following is a specification, reference being had to the accompanying drawings.

10 This invention relates to fountain brushes and has for its primary object to provide a device of this character which may be conveniently used as a shoe blacking or stenciling brush.

15 It is another and more particular object of the invention to provide a container or reservoir having a spring-pressed plunger therein and a polishing brush fixed to one side of the reservoir, said reservoir having 20 an outlet nipple at one end, a valve disposed contiguous to the open end of the nipple, a dauber movable upon the nipple, and means yieldably urging the dauber in one direction and preventing the passage of the liquid 25 past the valve.

It is a further general object of my invention to improve and simplify the construction of brushes of the above character, whereby the same are rendered highly serv- 30 iceable and convenient in practical use and capable of manufacture at relatively small cost.

With the above and other objects in view, my invention consists in the novel features 35 of construction, combination and arrangement of parts to be hereinafter more fully described, claimed and illustrated in the accompanying drawing, in which,

Figure 1 is a vertical sectional view illustrating the preferred embodiment of my improved fountain brush;

Fig. 2 is a section taken on the line 2—2 of Fig. 1;

Fig. 3 is a section taken on the line 3—3 of Fig. 1;

Referring in detail to the drawing, 5 designates a container or reservoir preferably constructed of sheet metal and which may be of either rectangular or cylindrical shape, 50 as preferred. To one side of this reservoir, a polishing brush 6 is suitably secured, said brush preferably extending substantially the entire length of the reservoir. To the opposite side of the reservoir 5, a suitable handle 7 is fixed.

A plunger 8 is arranged within one end

of the reservoir and, to the periphery thereof, one end of a guiding sleeve or annulus 9 is secured. To one side face of the plunger 8, the large end coil of a spiral spring 10 is 60 secured. The coils of this spring successively decrease in diameter so that they will nest within each other, and the smaller end coil is centrally fixed, as at 12, to the wall of a closure cap 11. This cap is provided with 65 an interiorly threaded flange for engagement with exterior threads on the open end of the container 5. It will thus be readily understood that when the cap is unthreaded from the end of the container, the plunger 70 and the spring may be removed so that the reservoir or container can be conveniently filled with the liquid.

The other end of the container is provided at its upper side with an angularly 75 projecting, outlet tube or nipple 13. A rod 14 extends within this nipple and is riveted or otherwise securely fixed at one of its ends to the wall thereof. A semi-spherical valve member 15 is threaded upon 80 the other end of this rod and has its convex face disposed in spaced relation to the open end of the nipple.

16 designates the head of a dauber brush in which the bristles, indicated at 17, are 85 suitably fixed. This head is provided in the face opposite to that from which the bristles project, with a central, circular cavity 18, and a plurality of orifices 19 are formed through the head 16 to conduct the liquid 90 from the cavity to the bristles 17. A metal plate 20 is fixed upon the head 16 over the cavity 18 thereof, and is centrally formed with an angularly projecting sleeve 21 which, at its juncture with the plate, is dia- 95 metrically enlarged or of bulbous formation, as indicated at 22. Normally, the wall of this enlarged portion of the sleeve is disposed in close contact with the convex face of the valve member 15 and prevents the 100 escape of the liquid around the valve member into the cavity 18 of the brush head. A cap or collar 21' has threaded engagement upon the sleeve 21, and within said collar and surrounding the nipple 13, the packing ring or gasket 21^a is arranged for engagement against the end of the nipple 21. Thus, leakage of the liquid between the nipple and the sleeve 21 is effectually prevented.

To the closed end of the container or 110 reservoir 5, one end of a leaf spring 23 is securely fixed. This spring is bent as

shown, and has its other end securely fixed to the plate 20 and the head 16, said latter end of the spring having an opening 24 therein to accommodate the enlarged end-portion 22 of the sleeve 21.

In the use of my improved brush, it will be understood that when the bristles 17 of the dauber are pressed against the shoe or other object, the dauber is forced inwardly 10 with respect to the nipple 13, against the action of the spring 23 so that the wall 22 is disengaged from the valve 15 and the blacking may then pass from the container into the cavity 18 and through the ducts or orifices 19 to the bristles 17. Immediately 15 upon the release of such pressure, the spring 23 returns the dauber to its normal position and cuts off the further supply of the liquid to the bristles 17. As the blacking or other 20 liquid within the container 5 is consumed, the spring 10 urges the plunger 8 inwardly and thus forcibly feeds the liquid through the outlet nipple. In the use of the device 25 as a shoe blacking brush, it will be understood that after the blacking has been applied to the surface of the shoe by means of the dauber, the shoe is polished by means of the brush 6.

From the foregoing description, the construction and manner of operation of my 30 invention will be clearly and fully understood. The device may be conveniently employed in stenciling, the dauber being engaged upon the stencil plate and the marking fluid used with a minimum of waste. It 35 will, of course, be manifest that the container or reservoir may be of any desired capacity and the dauber, whereby the fluid is applied, can likewise be of other shapes 40 and sizes than that indicated in the drawing. The invention is likewise susceptible of a great many minor modifications in the form, proportion and arrangement of its detail

parts and I, therefore, reserve the privilege of adopting all such legitimate changes as 45 may be fairly embodied within the spirit and scope of the invention as claimed.

Having thus fully described my invention, what I desire to claim and secure by Letters Patent is:

1. A fountain brush including a reservoir having an outlet nipple on one end, a dauber provided with a sleeve slidably engaged upon said nipple and having its wall formed with a valve seat, a member fixed within the nipple and projecting beyond the open end thereof, a valve element adjustable upon said member with respect to the open end of the nipple, and a leaf spring fixed at one of its ends to the reservoir and at its other end to the dauber and yieldingly urging the dauber in one direction to engage the valve seat with the valve and close the outlet nipple.

2. A fountain brush including a reservoir having an outlet nipple at one end, a removable, spring-pressed feeding plunger in the other end of the reservoir, a relatively stationary valve disposed in spaced relation to the open end of said nipple, a dauber having a head provided with a central cavity, a plate fixed to the head over said cavity and having a central, angularly projecting sleeve slidably engaged on the nipple, said sleeve having a valve seat formed in its wall and a leaf spring fixed at one end to the reservoir and at its other end to said plate to urge the dauber in one direction and engage the valve seat with said valve and normally close the outlet.

In testimony whereof I hereunto affix my signature in the presence of two witnesses.

WILLIAM T. SNYDER.

Witnesses:

C. F. ROBERTS,
HARRIS HARTWELL.
